(57) CLAIM

I claim the ornamental design for a button based actuator, as shown and described.

DESCRIPTION

FIG. 1 is a perspective view of a button based actuator.

FIG. 2 is a front view thereof;

FIG. 3 is a back view thereof;

FIG. 4 is top view thereof;

FIG. 5 is a bottom view thereof;

FIG. 6 is a right view thereof;

FIG. 7 is a left view thereof;

FIG. 8 is a perspective view thereof with broken lines showing holding clips attached to the button based actuator; and,

FIG. 9 is a perspective view thereof with broken lines showing a support rail to which the button based actuator is attached to.

The broken lines form no part of the claimed design.
